UNITED STATES PATENT OFFICE

2,588,137

DEVICE FOR CONTROLLING FLUID FLOW

Philip R. Marvin, Wauwatosa, Wis., assignor to
Milwaukee Gas Specialty Company, Milwaukee,
Wis., a corporation of Wisconsin

Application March 10, 1947, Serial No. 733,593

5 Claims. (Cl. 137—139)

1

This invention relates, in general, to apparatus for controlling fluid flow in conduits, and has particular relation to an improved burner control valve.

While the particular apparatus which I shall describe hereinafter in connection with the drawing is, in general, of the type in which the valve is controlled by an electromagnet connected in circuit with a thermoelectric generator, such as a thermocouple or thermopile, it is to be understood that the valve is not limited to this particular use but may, within the broader aspects of the invention, be controlled thermostatically or otherwise as suitable or desired.

One of the main objects of the present invention is to provide an improved form of valve which will operate quickly and in a positive manner, and in which an auxiliary valve operable by external means controls a cumulative pressure differential on opposite sides of a main valve member, whereby the main valve member is actuated to open or closed positions by the pressure of the fluid in the conduit.

Another object of the invention is to provide in a valve of the character described a new and improved combination of main and auxiliary valve members in which the by-pass port under the control of the auxiliary valve member is formed through the main valve member, and in which the auxiliary valve member cooperates with the main valve member to close such port and in the direction in which the main valve member seats on its valve seat whereby the auxiliary valve member assists, or may assist, the movement of the main valve member to closed position.

Another object of the invention is to provide an improved combination of main and auxiliary valve members in which the auxiliary valve member, in its movement to closed position, not only assists in moving the main valve member to closed position but assists in holding it in closed position whereby to maintain positive closure of the main valve without relying entirely on the dropping of the main valve member to closed position.

Another object of the invention is to provide an improved combination of main and auxiliary valve members in which the main and auxiliary valve members and the by-pass port under the control of the auxiliary valve member are concentrically disposed to provide a structure which is simple and compact and effective in use.

Another object of the invention is to provide a new and improved combination of a valve of

2

the character set forth, with an electromagnet connected in circuit with a thermoelectric generator whereby, through the instrumentality of the relatively minute thermoelectric E. M. F. generated by the heat of a pilot light or other flame on the thermoelectric generator the auxiliary valve member, and thereby the main valve member, may be actuated from one position to another, and, more particularly, from closed position to open position.

Another object of the invention is to provide an improved form of electromagnet and, more particularly, an electromagnet having a cup-shaped magnet frame for cooperation with a valve member and, more particularly, with an auxiliary valve member of the character described in a manner to actuate the same from closed position to open position through the instrumentality of the relatively minute thermoelectric E. M. F. generated by the heat of a pilot light or other flame on the thermoelectric generator.

Further objects and advantages of the invention will be apparent from the following detailed description, taken in connection with the accompanying drawing in which:

Figure 1 is a longitudinal and more or less diagrammatic section through a valve embodying the invention, and showing the main and auxiliary valve members in closed positions and a thermoelectric generator in position to be subjected to the heat of a pilot flame and connected in circuit with the electromagnet at the valve; and

Figure 2 is a fragmentary longitudinal and more or less diagrammatic section showing a modified form of valve.

Referring now to Figure 1 of the drawing, the burner shown at 1 is a main burner. It may be the main burner for a room or space heater, or it may be the burner for a water heater or for a floor-furnace, an oven burner, one or more top-burners for a gas range, or any other burner, and of any suitable construction.

45 A fuel supply pipe or conduit 2 leads to the burner 1 for the delivery of gaseous or other fuel thereto, for example, through a mixing chamber 3 to which air is admitted through adjustable air inlets (not shown), as well understood in the art. The flow of gas through the conduit 2 is controlled by a valve 4.

The pilot burner 5, which is located in juxtaposition to the main burner 1 to maintain a pilot flame 6 for igniting the main burner, is supplied 55 with gaseous fuel by a pilot-supply pipe 7. The

pilot supply pipe 7 may be connected, for example, to the pipe 2 anterior of the valve 4, or through this valve, or, in some cases, posterior of the valve member within the body of the valve 4, or to any other source of fuel supply.

The valve 4 comprises a valve body 10 having an inlet 11 and an outlet 12. Contiguous sections of the fuel pipe 2 are connected to the inlet 11 and outlet 12, for example, by screwing them into the inlet and outlet which are shown as internally threaded. Internally the valve body 10 is provided with a generally L-shaped outlet chamber 13 having a longitudinally extending part in open communication with the outlet 12, and a transversely extending portion defined by a cylindrical wall 14. The wall 14 terminates in an annular valve seat 15. An inlet chamber 16, in open communication with the inlet 11, terminates at its inner end in an annular shaped portion which embraces the cylindrical wall 14 of the outlet chamber.

A pressure-accumulating chamber 18 of circular or other configuration is provided in the valve body 10 above and concentric with the valve seat 15, and is of a diameter substantially equal to that of the adjacent portion of the inlet chamber and greater than the outside diameter of the valve seat 15. A main or primary valve 20 of disc-like form is adapted to seat against the valve seat 15. The valve 20 is adapted to extend beyond the marginal edges of the seat 15 within the confines of the pressure chamber 18 and may conform to the general shape of the pressure chamber, but is of slightly lesser diameter, thus providing a relatively small clearance gap 21 between the outer marginal edge of the valve 20 and the inner periphery of the wall of the pressure chamber.

A cover 22 for the valve body 10 is maintained in assembled relation thereto, for example, by screws 23, and provides a closure for the outer end of the pressure chamber 18. A gasket 24 may be provided to make the joint between the valve body 10 and the cover 22 fluid-tight.

A by-pass port 25 is formed through the valve 20, for example, concentrically thereof, as shown in the drawing. The port 25 is under the control of an auxiliary valve 26 of disc-like form. The auxiliary valve 26 operates directly in the chamber 18 and cooperates with the main valve 20 to close the port 25 in the direction in which the main valve 20 seats on its valve seat 15. In this way the movement of the auxiliary valve 26 to closed position seats against the main valve 20, and thereby assists the movement of the main valve to closed position, and in maintaining positive closure of the main valve member without relying entirely on the dropping of the main valve member to closed position. The auxiliary valve 26 may be prevented from displacement laterally to position uncovering the port 25, for example, by guide pins 46 on the main valve 20.

The foregoing advantages are not accomplished where the auxiliary valve does not seat against the main valve, for example, where the auxiliary valve is spaced laterally of the main valve. The structure described also eliminates the necessity of a laterally spaced by-pass port in the valve body, and the necessity of a conduit or passage leading from the chamber 18 to such a port. Moreover, the structure described makes it possible to provide an improved and more compact relation between the auxiliary valve and the operating means therefor, and eliminates the

necessity of levers or the like extending laterally to such a laterally disposed auxiliary valve.

In the illustrated embodiment of the invention, the means for operating the auxiliary valve 26, and, more particularly, the means for actuating this valve to open position, is shown in the form of an electromagnet comprising a magnet frame 28 having its coil 29 connected by lead conductors 30 in circuit with a thermocouple 31. The thermocouple 31 and lead connections therefor may be of the general character disclosed and claimed in Oscar J. Leins Patent No. 2,126,564, granted August 9, 1938, or it may be of any other suitable character, or in the form of a thermopile or other thermoelectric generator. The thermoelectric generator has one or more hot junctions, for example the hot junction 32, which is placed in position to be heated by the flame 33 of a burner, such as the pilot burner 5.

In the illustrated embodiment of the invention, the magnet frame 28 is shown of cup-shaped form having an annular groove 34 forming at the axis of the magnet frame, which may be of cylindrical form, a cylindrical stem part 35. The coil 29 is wound around the stem part 35 and is disposed within the groove 34. This provides an advantageous form of electromagnet which is adapted for drawing the auxiliary valve 26 to its open or attracted position, shown in dotted lines, by the relatively weak thermoelectric E. M. F. generated by the heat of the flame 33 on the hot junction 32 of the thermocouple.

In Figure 1 the magnet frame 28 is shown held to the cover 22 by means of a bracket 36 secured in place by a screw 37. Suitable cementing material may be provided at 38. These features may, of course, vary widely, and it is to be understood that the auxiliary valve 26 may, within the broader aspects of the invention, be controlled thermostatically or otherwise as desired, instead of thermoelectrically as shown and described.

While the auxiliary valve 26 of the illustrated embodiment of the invention operates to retracted or closed position by gravity, it is to be understood that a relatively weak coiled spring or the like may be provided for moving or assisting the movement of the valve 26 to closed position when the pilot flame 33 is extinguished.

It is also to be understood that the gas in the compartment 18 may be maintained out of contact with the electromagnet, for example by a partition 40, as shown fragmentarily and more or less diagrammatically in Figure 2. In such case the auxiliary valve member 26', which corresponds with the auxiliary valve member 26 of the preceding embodiment of the invention, instead of constituting also the armature for the electromagnet, may be connected by a stem 41 with an armature 42 within the sealed compartment 43, and the opening in the partition 40 through which the stem 41 operates slidingly may be provided with suitable packing (not shown) to prevent gas leakage therethrough.

When the auxiliary valve member 26 moves to position closing the port 25, for example, upon being released by the electro-magnet when the pilot flame is extinguished, the momentum of the flow of fluid through the inlet chamber 16 and upwardly toward the valve member 20 causes a momentary continuation of fluid flow through the gap 21 between the valve member 20 and the walls of the pressure chamber 18. Since the outlet port 25 is now closed, this produces a sudden increase in static pressure in the pressure chamber 18 above the valve 20. This

disrupts the previous relation of forces acting upon the valve 20, and creates a differential in favor of the forces above the valve 20.

The valve 20 therefore not only moves toward seated position on its seat 15, but this movement is assisted by the cooperation of the auxiliary valve member 26 with the main valve member 20. As the movement of the valve 20 to closed position takes place, the valve 20 cuts off a portion of the former flow of fluid into the outlet chamber 13. The momentum of fluid in the line beyond the outlet port produces a momentary reduction of static pressure in the outlet chamber 13, which further unbalances the forces formerly maintaining the valve 20 in open position. Thus the valve 20 is urged toward a seated position with a progressively increasing differential of forces and is finally impelled against the valve seat 15 with a positive snap-like action which is augmented by the action of the auxiliary valve member 26 on the main valve member 20. Once the main valve 20 is in closed position, the static fluid pressure on the inlet side thereof operates against the upper surface of the valve member 20 and auxiliary valve member 26 to maintain the valve member 20 in a seated position. The auxiliary valve member 26 also acts to maintain positive closure of the main valve 20 without relying entirely on the dropping or movement of the main valve member to closed position.

When the pilot burner 5 is ignited, the heat of the pilot flame 33 on the hot junction of the thermocouple sets up a flow of thermoelectric current through the coil 29 of the electro magnet. This energizes the electromagnet sufficient- 10 ly to draw the auxiliary valve member to attracted or open position as shown in dotted lines in Figure 1. The fluid in the pressure chamber 18 then seeks, through the port 25, an even pressure with that of the outlet chamber 13. Due to the fact that the gap 21 between the valve 20 and the adjacent walls of the pressure chamber 18 is restricted in sectional area, fluid moves through the port 25 into the outlet chamber at a greater rate than that of incoming fluid through the gap 21. Thus the pressure against the upper surface of the valve 20 is relieved, and since a flow of fluid is now taking place through the inlet chamber 16 toward and around the valve 20, a dynamic or impingement pressure against the under side of the valve 20 is added to the inlet static pressure, thus overcoming the reduced pressure against the upper side of the valve 20 and the auxiliary valve 26 thereon, and causing the valve 20 to move away from the seat 15.

As the volume of fluid flow through the device increases, the dynamic pressure against the under side of the valve — being a function of the fluid velocity — likewise increases and causes the valve 20 to move away from the valve seat 15 to a position allowing full flow of fluid through the device. The open position of the valve 20 is shown in dotted lines in Figure 1. The valve, when in open position presents no material restriction to the flow of fluid therethrough and causes no undesirable pressure drop by reason of its presence in the line.

The port 25 through the first valve disc 20 is of a size so that when the auxiliary valve disc 26 is open the gas will flow out through the port 25 from the pressure chamber 18 to the outlet chamber 13 faster than it will flow from the inlet chamber 16 into the pressure chamber 18 around the periphery of the valve disc 20. The

annular area of the bottom portion of the first valve disc 20 which extends peripherally beyond valve seat 15 is exposed to the pressure in the inlet chamber 16, and of such character when the auxiliary valve disc 26 is open the upward forces will over-balance the downward forces, with a resulting opening of the first valve disc 20. When the second valve disc 26 is closed against the first valve disc 20, the downward forces on valve discs 20 and 26 over-balance the upward forces on the peripheral extension of valve disc 20 beyond valve seat 15, with a resulting closing of the first valve disc 20.

Whenever the valve disc 26 is actuated to open position and held in open position by energization of the electromagnet, the action of the pressure of the gas in the inlet chamber against the annular area of the bottom portion of the valve disc 20, which extends peripherally beyond the valve seat 15, exceeds the tendency of the action of the pressure in the pressure chamber 18 to seat the valve disc 20 and actuates the valve disc 20 to open position. It is immaterial whether the valve disc 20 is held in some intermediate position or moves to its upper limit. In any event the valve disc 26 will at this time be held attracted to the electromagnet, and the forces holding the valve disc 20 in open position will exceed any forces tending to close the valve disc 20. Moreover, the guide pins 46 on the valve disc 20 may, by cooperation with the electromagnet when the valve disc 20 is in its uppermost position with the valve disc 26 in attracted position, provide a space between the valve discs 20 and 26.

However, upon deenergization of the electromagnet, the valve disc 26 moves to position seating upon the valve disc 20 and closing the port 25. The downward forces on the valve discs 20 and 26 presented by the gas pressure in the pressure chamber 18 and, for example, the weight of the valve discs, or by the action of a spring as previously set forth, now exceed the forces tending to hold the valve disc 20 open, and this valve disc 20 moves to closed position seating upon the valve seat 15.

The embodiments of the invention shown in the drawing are for illustrative purposes only, and it is to be expressly understood that said drawing and the accompanying specification are not to be construed as a definition of the limits or scope of the invention, reference being had to the appended claims for that purpose.

I claim:

1. In a gaseous fuel control valve, in combination, a valve body having an outlet port surrounded by a valve seat and communicating with an outlet chamber, a first thin, light weight disc valve of planar form adapted to seat upon said valve seat, said valve body having an inlet chamber on the same side of said first valve disc as said outlet port and said outlet chamber, said valve body having a static fluid pressure chamber in communication with said inlet chamber and disposed adjacent said valve seat, said static fluid pressure chamber being disposed on the opposite side of said first valve disc, said first valve disc extending peripherally beyond said valve seat and over said inlet chamber whereby fluid entering said inlet chamber is adapted to act directly against the peripheral extension of said first valve disc, said first valve disc having an outer diameter slightly less than the inner diameter of the adjacent portion of said pressure chamber to provide only restricted communica-

tion between said inlet chamber and said pressure chamber around the periphery of said first valve disc, said first valve disc having a port opening therethrough from said pressure chamber to said outlet chamber, a second thin light weight disc valve of planar form disposed in said pressure chamber and adapted to seat upon said first valve disc to close said port, the port through said first valve disc being of a size for the flow of gas out therethrough from said pressure chamber to said outlet chamber faster than it will flow into the pressure chamber around the periphery of said first valve disc when said second valve disc is unseated and the annular area of the first valve disc which is exposed to the pressure in the inlet chamber being of such character that the upward forces will overbalance the downward forces when the second valve disc is unseated with a resulting unseating of said first valve disc, the downward forces on the first and second valve discs when the second valve disc is seated overbalancing the upward forces with a resulting seating of said first valve disc, and means for unseating said second valve disc.

2. A valve according to claim 1 wherein there is means on said first valve disc which cooperates with said second valve disc to prevent undue lateral displacement of said second valve disc relative to said first valve disc.

3. A fluid valve according to claim 1 wherein there is projecting means on said first valve disc cooperating with the outer periphery of said second valve disc to prevent undue lateral displacement of said second valve disc relative to said first valve disc.

4. A fluid valve according to claim 1 wherein there is a partition covering and sealing the outer side of said pressure chamber and wherein the second valve disc has a stem projecting through said partition.

5. A fluid valve according to claim 1 wherein the means for unseating the second valve disc comprises an electromagnet connected in circuit with a thermoelectric generator and disposed to unseat the second valve disc upon energization of said electromagnet by said thermoelectric generator.
